DESIGN FOR A TEXTILE FABRIC OR SIMILAR ARTICLE

William Wichmann and Alfons Koppel, New York, N. Y.

Application May 11, 1938, Serial No. 77,111

Term of patent 3½ years

To all whom it may concern:

Be it known that we, William Wichmann and Alfons Koppel, citizens of the United States and residents of Manhattan, in the city, county, and State of New York, have invented a new, original, and ornamental Design for a Textile Fabric or Similar Article, of which the following is a specification, reference being had to the accompanying drawing, forming part thereof.

The figure of the drawing is a plan view of a textile fabric or similar article showing our new design.

The design unit is contained between the dot and dash lines, which unit is repeated in regular succession, as indicated by the extensions beyond the unit boundaries.

We claim:

The ornamental design for a textile fabric or similar article, substantially as shown and described.

WILLIAM WICHMANN.
ALFONS KOPPEL.
